UNITED STATES PATENT OFFICE.

EDWARD H. EARNSHAW, OF ORANGE, NEW JERSEY, ASSIGNOR TO THE UNITED GAS IMPROVEMENT COMPANY, OF PHILADELPHIA, PENNSYLVANIA, A CORPORATION OF PENNSYLVANIA.

TAR-EXTRACTOR.

No. 907,583.

Specification of Letters Patent.

Patented Dec. 22, 1908.

Application filed April 11, 1908. Serial No. 426,433.

To all whom it may concern:

Be it known that I, EDWARD H. EARN-
SHAW, a citizen of the United States, residing
at Orange, in the county of Essex and State
5 of New Jersey, have invented certain new
and useful Improvements in Tar-Extractors,
of which the following is a specification.

Objects of the present invention are to
provide a tar extractor which shall be com-
10 pact and capable of use even in cellars and
efficient under wide variations of gas flow;
to control the movements of the gas bell in
such manner that they are not too sudden
and are not exaggerated; to provide for ar-
15 ranging the parts which seal the counter-
balancing connections of the bell within the
shell or casing; and to provide for presenting
the same number of perforations in each of
the walls of the bell for the passage of gas in
20 any position of the bell, it being understood
that the number of perforations presented
in each wall is always the same but the
number of course differs for different posi-
tions of the bell.
25 The invention will be finally claimed but
one embodiment of it will first be described
in connection with the accompanying draw-
ings in which—

Figure 1, is a transverse central vertical
30 section of a tar extractor embodying features
of the invention. Fig. 2, is a similar view
showing part of the extractor with the mem-
bers thereof in different positions from those
35 shown in Fig. 1. Fig. 3, is a sectional view
drawn to an enlarged scale and illustrating
the disposition of the perforations in the
walls of the bell. Fig. 4, is a view illustrat-
40 ing an arrangement of the perforations in the
walls of the bell. Fig. 5, is a similar view
showing a modified arrangement, and Fig.
6, is a horizontal sectional view illustrating
45 features of construction.

In the drawings 1, is a casing having a gas
inlet pipe 2, projecting upward through its
45 base to afford space for a liquid seal 3.

4, is a gas off-take connection from the
casing.

5, is an overflow connection which is suit-
ably sealed.

50 6, is a draw-off connection for tar shown
as provided with a suitable valve or stop-
per 7.

8, is a movable bell arranged in the shell.
There is an opening 9, through the top of the

shell and from this opening depends a tube 55
10. There is also an opening through the
top of the bell from which depends a tube 11,
arranged concentrically with the tube 10. A
rod 12, is connected with the lower end of
the tube 11, as by means of a spider 13. The 60
upper end of this rod 12, is attached to
the chain 14, which runs over pulleys or
wheels 15 and 16, of which one is arranged
at the top and the other at the side of the
casing, and the chain carries at its end a 65
weight 17, which is sufficient to partially
counter-balance the weight of the bell 8, and
connected parts.

There is a well 18, shown as arranged in the
projecting end of the gas inlet pipe 2, and 70
supported by spiders 19. Into this well the
lower ends of the tubes 10 and 11, dip.
Thus the outlet at the top of the casing is
sealed in all positions of the bell.

20, is a duct communicating with the well 75
18, and with the seal space at the bottom of
the casing 1, so that the well is kept full
from the contents of the casing.

The depending walls of the bell encircle
the end of the inlet pipe 2, and are arranged 80
to dip into the liquid seal 3. The walls 21,
22, 23, 24, and 25, of the bell are concentric
and each wall is provided with groups of per-
forations. The groups of perforations in the
succeeding walls are in staggered relation as 85
shown in Fig. 6. Considering all the groups
of perforations of each wall, the perforations
are less numerous at the top than they are
at the bottom and considering the walls suc-
cessively from the inside to the outside, the 90
highest perforations in each wall are ar-
ranged nearer to the top of the bell than in
the preceding wall. In Fig. 4, the groups
of perforations are shown at 26, and in Fig.
5, they are shown at 27, and less perforations 95
in the aggregate are presented at the top
than at the bottom in Fig. 4, by gradually
diminishing the number of perforations in
each group, and in Fig. 5, by extending some
of the groups nearer to the top than the 100
others. Since the groups are staggered, a
blank space 28, is presented opposite each
group of perforations 26, as shown in Fig. 6.

29, is a flange projecting inward from the
shell 1, and arranged in the seal space. 30, 105
is a similar flange arranged at a somewhat
higher elevation than the flange 29. Each
of these flanges is shown as extending about

half way around the casing. 31, and 32, are similar flanges projecting from the external wall of the shell. The purpose of these flanges is to control the movements of the bell and of the liquid between the bell and casing.

Assuming the parts to be in their normal positions, as shown in Fig. 2, then upon the passage of gas through the apparatus, as indicated by the arrows in Fig. 1, the pressure of the gas lifts the bell 8, more or less high according to changes in the rate of flow of gas, but unduly sudden or violent movements of the bell are opposed by the flanges on the bell and casing which, in connection with the liquid of the seal 3, oppose any tendency to such sudden or violent movements but do not interfere with the necessary gradual rise and fall of the bell. The gas passes through the perforations of the groups 26, strikes the blank spaces opposite them and thus tar and moisture are extracted as is well understood. However, since the aggregate number of perforations in each plate is smallest near the top thereof and increases toward the bottom thereof, it follows that any given increase in the rate of flow of gas will demand a length of rise in the bell which is greater in the lower than in the higher positions of the bell; this makes the apparatus more delicate in operation at low rates of flow of gas. There is a loss of pressure from the center of the bell outward so that the liquid seal 3, does not stand at the same level but at levels progressively higher, as shown in Fig. 1, when the gas is passing. The fact that the perforations are progressively arranged higher up in each succeeding wall from the center of the bell to the outside thereof, as shown in Fig. 3, causes the same number of perforations to be uncovered in each wall although the top of the seal is at progressively higher levels as has been described, and in this way the requisite velocity of the gas is approximately the same through the perforations of all the successive walls. Of course in different positions of the bell the number of perforations uncovered in each wall is the same but this number varies according to the height of the bell. The tubes 10 and 11, in connection with the well 18, prevent the escape of gas through the opening 9, and since these parts are arranged within the interior of the device so as not to project from it, the

device can be arranged in a relatively small space such as the cellar of the gas works.

What I claim is:

1. In a tar extractor the combination of a casing having inlet and off-take connections and a space for a liquid seal, a movable partially counter-balanced bell arranged in the casing and having perforated side walls dipping into the liquid seal, and complementary flanges arranged in the liquid seal and respectively projecting from the outer wall of the bell and the inner wall of the casing to govern the movements of the bell, substantially as described.

2. A tar extractor comprising the combination of a casing having inlet and off-take connections and a liquid seal, and a movable bell arranged in the casing and having a series of depending walls dipping into the liquid seal and provided with staggered groups of perforations, the perforations in each wall being less numerous at the top than at the bottom of the wall and the perforations in the respective walls being arranged higher up progressively from the interior toward the exterior of the bell, substantially as described.

3. A tar extractor comprising a casing having outlet connections and an opening in its top and an inlet pipe projecting through its bottom to form a liquid seal space, a movable bell arranged in the casing, complementary flanges projecting respectively from the casing and bell and arranged in the liquid seal, counter-balancing connections arranged through the opening in the top of the casing and connected with the bell, a well in the casing, tubes depending from the casing into the well and respectively connected with the tops of the casing and bell, and the bell having a series of depending walls having staggered groups of perforations, the perforations being less numerous at the top of each wall than they are at the bottom and the perforations extending higher toward the tops of the walls progressively in the various walls from the center of the casing outward, substantially as described.

In testimony whereof I have hereunto signed my name in the presence of witnesses.

EDWARD H. EARNSHAW.
